APPARATUS FOR WINDING

Ernest K. Bauer, Meadville, Pa., assignor to American Viscose Corporation, Wilmington, Del., a corporation of Delaware

Application April 6, 1946, Serial No. 660,221

18 Claims. (Cl. 28—38)

1

The present invention is concerned with methods and apparatus for winding and has as its main object maintaining a uniform pressure on the winding periphery during the winding operation.

While it has heretofore been suggested to maintain such a uniform pressure by using either a pneumatic or hydraulic fluid-pressure means, the devices of the prior art had the disadvantage that if a slight distortion at some part of the periphery of the winding, such as a bulge, occurred, the fluid-pressure device would tend to vibrate as a result of allowing the pressure element to be moved outwardly from the axis of the winding at the position of the bulge and then to return toward the axis of the winding as it left the bulge. During high speed winding, the fluctuations of the pressure elements that result from hitting one or more such bulges about the periphery, tends to cause "chattering" or vibration and an unsatisfactory winding in spite of the tendency of the fluid-pressure means to maintain a constant pressure against the winding.

It is the main object of the present invention to avoid such fluctuations of the pressure element and in doing so, it has been found that a more satisfactory winding is obtained, any localized bulges occurring during the winding being more or less subdued rather than accentuated by the improved operation in accordance with the invention. Other objects and advantages of the invention will be apparent from the drawing and the description thereof hereinafter.

In the drawing, which is illustrative of the preferred embodiment for carrying out the invention—

Figure 1 is a side elevation with parts broken away of a beamer to which the invention has been applied, and

Figure 2 is a plan view of the beamer as shown in Figure 1.

In general, the present invention involves winding a material, such as one or more yarns, which may or may not be traversed relative to the rotatable element upon which winding occurs, while maintaining a pressure roller against the periphery of the winding and controlling the pressure of the roller by fluid means. The pressure roller is displaced outwardly from the axis of the winding element during winding by virtue of the increase in diameter thereof but the pressure roller is not allowed to return toward the axis of the winding element at any time during the winding thereof. If there is any slight bulge of the winding periphery, such bulge displaces the pressure roller from the axis of the winding element and the fact that it is a bulge tends to make the displacement slightly greater than the properly laid portion of the winding which is unbulged. How-

ever, this tendency to greater displacement is counteracted to a certain extent by the inertia of the pressure roller so that the bulge tends to be minimized by compaction of the pressure roller. However, after the bulged portion has turned past the pressure roller, the pressure roller is not allowed to return toward the axis of the winding element, so that the balance of the next convolution is allowed to be compacted to a slightly less extent than ordinary to compensate for the different diameters of the bulged and unbulged portions. By such a winding procedure, the bulges cannot be accentuated but tend to be evened out and a more satisfactory final package is obtained.

As shown in the drawing, the invention is applied to a beamer to which a sheet of yarns is fed, such as from a creel. When winding a warp sheet, there is generally no traverse applied to the yarns. However, the invention is also applicable to the winding of a single yarn while traversing the yarn back and forth axially of the package. It is, of course, applicable also to the winding of two or more yarns side by side by traversing them. It may also be used in machines for winding fabrics, sheets, such as of paper or cellophane, etc.

With reference to Figures 1 and 2, the rotatable winding element 2 is constituted of a warp beam. This beam is mounted with its axis 3 rotatable in suitable bearing elements 4 carried on the frame 5. A pressure roller 6 has trunnions 7 mounted rotatably in the plates 8 of a yoke carried by the two side rods 9. This yoke pivots about an axis 10, and one or more rods 11 (two being shown), coupled to the cross bar 12 of the yoke for the pressure roller 6 by means of pivotal joints 13, are connected to pistons 14 operating in cylinders 15.

The pressure in the cylinders back of pistons 14 which urges the pressure roller 6 against the periphery of the winding may be derived from a fluid contained in tanks 16 which are connected to the back end of the cylinders by means of conduits 17. The pressure of the fluid within the tanks 16 may be controlled by means of a regulating or reducing valve 18 in a line 19 connecting the tanks 16 to a source of high pressure fluid. The line 19 is connected to two branches 20 leading to the tanks 16. While the fluid contained in tanks 16 may be liquid, such as oil, it is preferably a gas, such as air, for reasons which will be explained more completely hereinafter.

The cylinder ends near the pressure roll are connected by lines 21 to the bottom of a reservoir tank 22 which contains a check valve 24 and a by-pass line 25 containing a valve 26.

Because of the swinging motion of the pressure roll support, the cylinders 15 are mounted for

3

pivotal motion about axis 27 and the lines 17 and 21 are of flexible material, such as rubber or synthetic rubbers.

Suitable means is provided for driving the winding element, and as shown this may comprise a motor 28, a reduction gear 29, shaft 30, sprocket 31, chain 32, and sprocket 33 secured to shaft 3.

The yarns Y to be wound pass over a guide, such as roller 34, which may or may not be traversed, to the region near the nip of the pressure roll with the winding periphery, i. e. adjacent the position of accretion.

The operation may be described as follows: In starting position the beam 2 is practically empty and the pressure roll 6 is urged into contact with the first turn of winding by virtue of displacement of pistons 14 to the extreme right as viewed in Figure 1. In this position, the pressure back of pistons 14 is maintained at the desired value by the reducing valve 18. As stated heretofore, it is preferable to use tank 16 as an air dome or accumulator, but one could also have a liquid supply within tank 16 sufficient to more than completely fill the portion of the cylinder back of piston 14 when the elements are in their starting position as just described. When operating with a liquid in tank 16, it may be desirable to connect the top of tanks 16 to a supply of compressed air or other gaseous medium rather than a compressed liquid for the purpose of maintaining the pressure on the system. By using compressed air whether or not it works upon a volume of liquid extending into the regions of the cylinders back of pistons 14, the assembly may have somewhat the action of a dashpot and the inertia exerted by the system in resisting the compressive force exerted by the piston when the pressure roll strikes a sudden bulge, tends to flatten the bulge. If the liquid supply in tanks 16 were to be omitted and merely a gaseous medium provided, any dashpot effect would be negligible. Of course, it is possible to have the entire system back of pistons 14 filled with liquid. This applies to the cylinders, lines 17, tanks 16, lines 20 and 19. This would cause the exertion of a maximum force of inertia tending to reduce any sudden bulges.

At the start of operation, with the pistons 14 at the extreme right of cylinders 15, valve 26 is closed and a check valve 24 allows liquid to flow by gravity from the tank 22 into the right ends of the cylinders to keep the space in front of the pistons 14 constantly filled with liquid. Since liquid is non-compressible the piston can only move in one direction away from beam.

As winding proceeds, the pressure roll 6 swings and causes piston 14 to move back in the cylinder. This occurs under substantially constant pressure controlled by the regulating valve 18 and liquid flows into the right ends of cylinders 15 to keep these ends full of liquid constantly. In case the pressure roll rides over a bulge or high spot in the winding, the fluid back of pistons 14 tends to reduce the bulge by virtue of inertia and by virtue of the fact that the liquid must flow through the conduits 17. After leaving the high spot, the pressure roll cannot return because of the fact that the right ends of cylinders 15 are full of liquid and the check valve closes against the return of liquid to tank 22. As explained hereinabove, this evens out the winding convolutions and produces a more satisfactory package.

When the winding is completed, the beam 2 can be replaced with an empty beam and pres-

4

sure rolls 6 may be returned merely by opening the valve 26. This by-passes the liquid around the check valve so that pistons 14 return to the right end of the cylinders under the pressure derived from the reducing valve 18.

It is to be understood that changes and variations may be made without departing from the spirit and scope of the invention as defined in the appended claims.

I claim:

1. In a winding machine, a rotatable element for receiving a winding thereabout, a rotatable pressure roller adapted to bear against the winding periphery, means for mounting the element and roller for relative movement to vary the distance between their axes, constant pressure fluid means for urging the roller periphery against the winding periphery, and hydraulic means for preventing relative movement of the roller and element toward each other during displacement by virtue of increasing diameter of winding on the rotatable element.

2. In a winding machine, a rotatable element for receiving a winding thereabout, a rotatable pressure roller adapted to bear against the winding periphery, means for mounting the element and roller for relative movement to vary the distance between their axis, constant pressure pneumatic means for urging the roller periphery against the winding periphery, and hydraulic means for preventing relative movement of the roller and element toward each other during displacement by virtue of increasing diameter of winding on the rotatable element.

3. In a winding machine, a rotatable element for receiving a winding thereabout, a rotatable pressure roller adapted to bear against the winding periphery, means for mounting the element and roller for relative movement to vary the distance between their axes, constant pressure hydraulic means for urging the roller periphery against the winding periphery, and hydraulic means for preventing relative movement of the roller and element toward each other during displacement by virtue of increasing diameter of winding on the rotatable element.

4. In a winding machine, a rotatable element for receiving a winding thereabout, a rotatable pressure roller, means for movably mounting the roller, constant pressure fluid means for urging the roller periphery against the winding periphery of the rotatable element, and hydraulic means for preventing return movement of the pressure roller during its displacement by virtue of increasing diameter of winding on the rotatable element.

5. In a winding machine, a rotatable element for receiving a winding thereabout, a rotatable pressure roller, means for movably mounting the roller, constant pressure pneumatic means for urging the roller periphery against the winding periphery of the rotatable element, and hydraulic means for preventing return movement of the pressure roller during its displacement by virtue of increasing diameter of winding on the rotatable element.

6. In a winding machine, a rotatable element for receiving a winding thereabout, a rotatable pressure roller adapted to bear against the winding periphery adjacent the position of accretion, means for movably mounting the roller, constant pressure hydraulic means for urging the roller periphery against the winding periphery of the rotatable element, and hydraulic means for preventing return movement of the pressure roller

during its displacement by virtue of increasing diameter of winding on the rotatable element.

7. In a winding machine, a rotatable element for receiving a winding thereabout, a support, mounting means pivotally connected to the support, a pressure roller mounted rotatably in the mounting means whereby the pressure roller is swingable toward and away from the element, constant pressure fluid means for urging the roller periphery against the winding periphery of the rotatable element, and hydraulic means for preventing return movement of the pressure roller during its displacement by virtue of increasing diameter of winding on the rotatable element.

8. In a winding machine, a rotatable element for receiving a winding thereabout, a rotatable pressure roller, means for swingably mounting the roller, constant pressure pneumatic means for urging the roller periphery against the winding periphery of the rotatable element, and hydraulic means for preventing return movement of the pressure roller during its displacement by virtue of increasing diameter of winding on the rotatable element.

9. In a winding machine, a rotatable element for receiving a winding thereabout, a movably mounted pressure roller adapted to bear against the winding periphery adjacent the position of accretion, a cylinder, a piston reciprocable in the cylinder, means connecting the roller to the piston for simultaneous interdependent movement, means for maintaining a fluid under constant pressure in the end of the cylinder away from the roller, means for maintaining the other end of the cylinder full of liquid during displacement of the piston away from the roller, and means for preventing any appreciable reduction in volume of the liquid in said other end of the cylinder during the winding.

10. In a winding machine, a rotatable element for receiving a winding thereabout, a movably mounted pressure roller adapted to bear against the winding periphery, a cylinder, a piston reciprocable in the cylinder, means connecting the roller to the piston for simultaneous, interdependent movement, means for maintaining a fluid under constant pressure in the end of the cylinder away from the roller, a liquid supply reservoir above the cylinder, a conduit from the reservoir to the end of the cylinder toward the roller, and a check valve in the conduit permitting flow of liquid from the reservoir to the cylinder but preventing flow in the opposite direction.

11. In a warping machine, a rotatable element for receiving a winding thereabout, a rotatable pressure roller adapted to bear against the winding periphery adjacent the position of accretion, means for mounting the element and roller for relative movement to vary the distance between their axes, constant pressure fluid means for urging the roller periphery against the winding periphery, and hydraulic means for preventing relative movement of the roller and element toward each other during displacement by virtue of increasing diameter of winding on the rotatable element.

12. In a warping machine, a rotatable element for receiving a winding thereabout, a support, mounting means pivotally connected to the support, a pressure roller mounted rotatably in the mounting means whereby the pressure roller is swingable toward and away from the element, constant pressure fluid means for urging the

roller periphery against the winding periphery of the rotatable element, and hydraulic means for preventing return movement of the pressure roller during its displacement by virtue of increasing diameter of winding on the rotatable element.

13. In a warping machine, a rotatable element for receiving a winding thereabout, a movably mounted pressure roller adapted to bear against the winding periphery adjacent the position of accretion, a cylinder, a piston reciprocable in the cylinder, means connecting the roller to the piston for simultaneous interdependent movement, means for maintaining a fluid under constant pressure in the end of the cylinder away from the roller, means for maintaining the other end of the cylinder full of liquid during displacement of the piston away from the roller, and means for preventing any appreciable reduction in volume of the liquid in said other end of the cylinder during the winding.

14. In a warping machine, a rotatable element for receiving a winding thereabout, a movably mounted pressure roller adapted to bear against the winding periphery, a cylinder, a piston reciprocable in the cylinder, means connecting the roller to the piston for simultaneous interdependent movement, means for maintaining a gaseous fluid under constant pressure in the end of the cylinder away from the roller, means for maintaining the other end of the cylinder full of liquid during displacement of the piston away from the roller, and means for preventing any appreciable reduction in volume of the liquid in said other end of the cylinder during the winding.

15. The machine of claim 1 in which the pressure roller presses the winding periphery adjacent the position of accretion.

16. The machine of claim 3 in which the pressure roller presses the winding periphery adjacent the position of accretion.

17. The machine of claim 4 in which the pressure roller presses the winding periphery adjacent the position of accretion.

18. In a winding machine, a rotatable element for receiving a winding thereabout, a rotatable pressure roller adapted to bear against the winding periphery, means for mounting the element and roller for relative movement to vary the distance between their axes, constant pressure means for urging the roller periphery against the winding periphery, and hydraulic means for preventing relative movement of the roller and element toward each other during displacement by virtue of increasing diameter of winding on the rotatable element.
